DESIGN.

C. T. GROSJEAN.

SPOON OR FORK HANDLE.

No. 15,144.

Patented July 15, 1884.

UNITED STATES PATENT OFFICE.

CHARLES T. GROSJEAN, OF NEW YORK, N. Y., ASSIGNOR TO TIFFANY & COMPANY, OF SAME PLACE.

DESIGN FOR A SPOON OR FORK HANDLE.

SPECIFICATION forming part of Design No. 15,144, dated July 15, 1884.

Application filed April 16, 1884. Term of patent 14 years.

To all whom it may concern:

Be it known that I, CHAS. T. GROSJEAN, a citizen of the United States, residing in the city, county, and State of New York, have invented and produced a new and original Design for a Spoon or Fork Handle, of which the following is a specification, reference being had to the accompanying drawings, forming part thereof.

10 The features of novelty of this design of spoon or fork handle consists, first, in a border of lines on the front and reverse surfaces which are undulating, so that it gives an effect of rippling water; second, in sea-weed bulbs interspersed at intervals over such surfaces, branching out from the border of lines; third, in the sea-shell at top of handle, on both sides, and also at heel of same.

In the drawings, Figure 1 is a view of the 20 front of a spoon-handle and its bowl. Fig. 2 is a view of the reverse surface or back thereof. Fig. 3 is a side view thereof.

In these drawings, *a* is a series of lines which encompass the border or edge and top 25 of the handle of the front and reverse surfaces, running in depressions and elevations alternately, (wave-like,) so as to give an undulating appearance to such front and reverse sur-

faces of the handle. When the handle is viewed as shown in Fig. 3, such undulating lines give the appearance of a series of bulbs resembling those found on sea-weed. The appearance at the front and reverse surface or back is like rippling water. At intervals branching out from these borders of undulating lines are representations of pieces of sea-weed, *b b*, &c. At the toe of the handle, on the front of the spoon or fork, is a representation of a bunch of sea-weed, *c*. On the reverse surface, at the heel of the handle, is a representation of a shell, *d*; also at the top of both front and reverse sides of the handle, within the undulating lines, are placed shells *d d*.

I claim—

1. The design of spoon or fork handle, consisting of a border of undulating lines, *a*, substantially as described and shown.

2. The design of spoon or fork handle, consisting of a border of undulating lines with sea-shells at top of handle and heel of same, substantially as described and shown.

CHAS. T. GROSJEAN.
